UNITED STATES PATENT OFFICE

ROBERT M. SELLECK, OF NEWARK, NEW JERSEY.

IMPROVEMENT IN COACH-HARNESS PADS.

Specification forming part of Letters Patent No. 173,819, dated February 22, 1876; application filed May 10, 1875.

To all whom it may concern:

Be it known that I, ROBERT M. SELLECK, of Newark, in the State of New Jersey, have invented an Improvement in Coach-Harness Pads, of which the following is a specification:

I make the metallic frame for the pad tubular at each side and composed of two plates, one of which is trough-shaped and receives the other or cap-plate that is riveted in place. The nuts for the terrets are introduced from the ends of the tubular frames, and the shanks of the terrets pass through the cap-plates into the nuts. The straps that pass beneath the cap-plate contain the nuts into which the pad-screws pass, and hold the parts firmly together.

In the drawing Figure 1 is a side view of the metal pad-frame; Fig. 2 is a vertical longitudinal section; Figs. 3 and 4 are cross-sections at the lines *x* and *y*, respectively; and Fig. 5 is a cross-section, showing a modification in the pad-frame.

The metal frame is made of the trough-shaped side pieces *a*, united together by the central portion *b*, having a hole through which the shank of the check-rein hook *d* passes, and is secured by the nut 2 in a recess below. There are also other openings through the side portions *a a*, through which the tacks, tufting, or stitches pass.

Each side piece *a* is provided with a covering-plate, *f*, that is of a shape to fit into its place and leave the frame hollow or tubular, and open at the ends in order that the nuts *g* of the terrets *h* may be passed in at the open ends and slide to place without disturbing the housing or coverings of the pad, and the terrets are screwed into said nuts to hold them firmly to the cap-plates of the hollow frames. These cap-plates *f* are secured to their places by rivets 5, and when these cap-plates are of malleable cast-iron the rivets may be cast therewith.

In cases where the edges of the side pieces *a* rise above the cap-plates *f*, as seen in Fig. 3, there will be a recess formed, in which the leather housing *i* will lie, and the material *l* that covers the padding *l'* will be brought up and over the edges of the frame *a*, and secured down into the angles of

the recess by cement or otherwise. But where the cap-plate *f* rests upon the edges of the frame *a*, as seen in Fig. 5, the covering material *l* will be drawn over the tubular frame and attached at the surface of the plate *f* by catch-threads or lacing from one edge of the covering to the other, and in that case the leather housing *i* will be finished at its edges by the binding-strip *t*, that is folded, attached to the under surface of the leather, and spread both upward at the edge of the leather and downward in a T form to cover the joint between the housing and the pad-covering *l*. This mode of securing the binding to the under side of the leather-housing is to be distinguished from a binding that has before been used where the folded strip is sewed to an intermediate layer of leather, and is not as strong, neat, and close-fitting as when secured to the leather housing itself.

The tubular metal frame, made in the form shown in Fig. 5, may be japanned, and it may have a covering of muslin, pasted or otherwise attached, and then japanned, and this covering may be attached to the metal frame before the padding or other covering is applied, to preserve the metal from rust or injury, if desired.

In order to make an easy and gradual termination to the metal frame where the girth-strap passes off from the pad, I employ the end pieces *u*, of either sheet metal or leather, attached to the ends of such side pieces *a*, and provided with edges or flanges for the strap *v* to lie between, and covered. These end pieces *u* will bend by the pressure to the shape of the animal, and appear much more graceful than an abrupt termination of the cast-metal frame.

The nuts 10 for the pad-screws 11 are attached to the straps *v*, and the straps passed in at the end of the pad beneath the plate *f*, and secured in place by the screws 11, that pass through the housing and said plate *f*.

I claim as my invention—

1. The harness-pad frame, made with tubular ends, composed of the trough-shaped portions *a* and cap-plates *f*, substantially as set forth.
2. The harness-pad frame composed of the trough-shaped frame *a* and cap-plates *f* above

such trough, leaving the ends of the frame open for the terret-nuts *g*, to be inserted from the ends, as set forth.

3. The removable side-straps *v*, having the nuts 10 attached to the under sides, and inserted into the open ends of the tubular frame *a f*, in combination with the pad-screws 11 that pass through the plate *f*, as set forth.

4. The pad-frame made with the edges of the metal *a* extending above the plate *f*, and over which the covering material *l* is drawn and secured, in combination with the housing-leather *i* introduced within the recess thus

formed in the metal pad-frame, substantially as set forth.

5. The combination, with the tubular metallic pad-frame, of the yielding pieces *u*, attached to the ends of the portions *a* of the frame, below and independent of the straps *v*, for the purposes set forth.

Signed by me this 6th day of May, A. D. 1875.

ROBERT M. SELLECK.
